UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

KEY-HOLDER FOR LOCKS.

978,965.

Specification of Letters Patent. Patented Dec. 20, 1910.

Application filed October 8, 1910. Serial No. 585,920.

To all whom it may concern:

Be it known that I, HENRY G. VOIGHT, a citizen of the United States, residing at New Britain, county of Hartford, State of Connecticut, have invented certain new and useful Improvements in Key-Holders for Locks, of which the following is a full, clear, and exact description.

My invention relates to an improvement 10 in locks, the object being to provide a simple and effective means for holding the key in the lock against accidental detachment, said means operating after the key has been inserted and turned to frictionally hold 15 the laterally offset bit of an ordinary key out of alinement with the key-hole, so that the key cannot be thrown out by slamming the door.

In the drawings Figure 1 is a side elevation 20 of a mortise lock with the cap removed, showing my improvement. Fig. 2 is a vertical section on the line $x-x$. Fig. 3 is a plan view of a detail.

1 represents the lock case, 2 a dead-bolt, 3 25 a tumbler therefor, 4 an ordinary key with an offset bit, and 5 an elongated key-hole. These parts thus far described are of the usual conventional form. Through the medium of the key, the operator manipulates 30 the tumbler or tumblers and advances or retracts the dead-bolt 2. To accomplish this advancement or retraction of the dead-bolt requires the turning of the key. After the key has been turned obviously the bit stands 35 out of alinement with the key-hole and cannot be removed.

My invention comprehends merely a simple device to frictionally hold the bit of the key in the out-of-line position. This device 40 comprises a curved spring 6, which is bent

down at the middle portion to stand under the lower end of the key-hole to allow the key to be inserted, and also bent down at its ends to project into pockets formed under lugs 7-7 preferably cast integrally with the 45 lower end of the lock case, said lugs simply operating as holders. The high parts of the spring stand on opposite sides of a plane passing directly through the key-holes in the lock, said high parts or humps standing 50 up sufficiently far so that they will engage the bit of the key as it is being returned toward the key-hole, requiring a manual act to overcome the tension of the spring in restoring the key to a position in which it can 55 be withdrawn. For example, as shown in Fig. 1, the key has been inserted and the bolt has been retracted thereby, the key being left in the door. As shown therein, the bitted end of the key is resting against one 60 of the humps in the spring 6. To remove it requires simply enough pressure to depress the spring 6 until the bit lines up with the key-hole 5.

What I claim is:

In a lock, an elongated key-hole passage arranged to receive a key having a laterally offset bit, a spring mounted on its ends below said key-hole, said spring being bent upwardly at two points intermediate its 70 length to form humps on opposite sides of a plane passing through said key-hole, and also bent down at the center sufficiently to permit a key to be inserted into the lock through the key-hole.

HENRY G. VOIGHT.
